(57) **CLAIM**

The ornamental design for a water container, as shown and described.

DESCRIPTION

The present application is related to commonly assigned U.S. Design Pat. No. D781,107 issued Mar. 14, 2017 and U.S. Design Pat. No. D781,657, issued Mar. 21, 2017.

FIG. 1 is a front left perspective view of a water container showing our new design.

FIG. 2 is a side view of the water container.

FIG. 3 is a view of the opposite side of the water container.

FIG. 4 is a front view of the water container.

FIG. 5 is a back view of the water container.

FIG. 6 is a top view of the water container; and,

FIG. 7 is a bottom view of a water container.

The broken lines in the drawings depict portions of the water container that form no part of the claimed design.
